UNITED STATES PATENT OFFICE

CHARLES W. HARRING, OF BROOKLYN, NEW YORK

OUTSIDE WINDOW SCREEN

Application filed June 22, 1927. Serial No. 200,575.

This invention relates to improvements in outside window screen.

Objects of this invention are to provide an outside screen or the like which may be more readily and quickly applied to a window frame than has heretofore been possible; to produce an outside frame for screen wire or the like that will, when closed, provide a tight joint with the outer surface of the window frame and that need not be made to fit the opening of the window frame with the same degree of accuracy as heretofore necessary; to provide an outside screen or the like which may be readily and quickly opened and in which all parts may be moved away from the window to permit ready cleaning of the outer surface of the glass of the inner sashes; and which may be readily retained in extended position; to produce an outside screen or like construction which will enable a facile mounting on the window frame and a mounting which may be concealed within the room to enable a more ornamental appearance from the outside of a screened or storm-sashed window to be produced.

With these and other objects in view, I will now describe and illustrate the invention as applied to a screen, it being understood that it may be equally well applied to an outside glazed sash; that the invention comprises the combination of members and arrangement of parts so combined as to coact and cooperate with each other in the performance of the functions and the accomplishment of the results herein contemplated, and comprises in one of its adaptations the species or preferred form illustrated in the accompanying drawings, in which:

Fig. 1 is an inside view, in perspective, of a screen embodying my invention, when removed from the window frame;

Fig. 2 is a vertical section of a window frame showing a window screen embodying my invention mounted in accordance with my preferred method of mounting;

Fig. 3 is a transverse section on the line 3—3 of Fig. 2;

Fig. 4 is an enlarged longitudinal section of a window frame and screen showing a

modified method of mounting; the screen being shown in open position; and

Fig. 5 is a view similar to Fig. 4, showing the same screen in closed position.

Referring now to these drawings, which illustrate a preferred embodiment of my invention, 1 indicates a window frame having a suitable window opening in which is mounted a screen 2.

In accordance with my invention the screen 2 is of slightly greater width and length than the opening of the window frame and is formed of edge members comprising side stiles 3, 3'; and top and bottom rails 4 and 5, forming a supporting frame for the wire 6, which frame is preferably reinforced by a middle-rail 7. An important feature of my invention comprises the provision in the edge of the screen frame of a rabbet 8 adapted to embrace the corners of the window frame 10 and particularly forming an outer flange 9 adapted to engage and lie flat against the outer face 10 of the window frame so that inward pressure or pull on the screen will enable a tight joint to be formed between the inner surface of said flange 9 and the outer surface of the stiles and top rail of the window frame. In view of the width of the flange, it will be seen that not only is a tight joint possible with the flat surface of the window frame, but the screen need not be made to fit with the same accuracy as screens adapted to fit within the window opening. This width of the flange also insures the provision of a tight joint between the bottom rail and the sill because it allows a slight downward movement to procure this tight fitting or contact. The rabbeting of the edge also provides an inner bar or rail 11 adapted to project within the window frame opening. This inner frame is preferably so proportioned as to provide a space between its side edge and the side of the window frame to permit the mounting of the screen by the connection of this side edge with the side or wall of the window frame, and in the preferred form of my invention illustrated, I secure to the side edges of these inwardly extending frame bars preferably above and below the middle section thereof, a pair of

100

links or swinging arms 12 adapted to provide an outwardly-extensible connection between the screen and the window frame which will enable all parts of the screen to be moved away from the window an equal distance and thus allow space for washing of the outer surface of the window glass without removing the screen. In the forms shown, the links are initially connected by screws to the edges of the inwardly-projecting bars 11 of the screen, the screen is fitted in place, the ends of these links 12 are then suitably positioned and their opposite free frame-engaging pivotal ends are then connected to the said frame, the screen being held in place by a hook 13 during the mounting or connection of the inner ends of the links to the window frame.

Upon disconnection of the hook, it will be apparent that the screen will be movable outwardly in substantially parallel relationship to the window frame as shown in Figs. 2, 3 and 4 and when these links are connected to the window frame at the points shown in Fig. 2, the screen will be automatically retained against further movement by gravity in its outwardly-extended position because of the contact or engagement of said arms with the window sill. On the other hand, if a connection, as shown in Figs. 4 and 5 is made, the screen though it may be similarly moved outwardly in parallel relationship to the window frame, will require some means for retaining the same in such position. In either case, however, room or space is provided for washing the outer surface of the window without dismounting the screens entirely.

In the preferred form of my invention, I preferably provide the middle rail of the screen with a handle 14 so as to enable the application of manual pressure to be applied centrally for the purpose of moving the screen to open position, and thus avoiding tilting and consequent jamming of the screen.

It will be seen that my invention completely eliminates all hooks and fixtures on the outside of the window frame; that it enables a more facile and quicker application of the screen to the window frame; that instead of providing for an accurate fit and contact of the outer edges of the screen with the edges of the window frame, I provide a flat surface which abuts against the flat outer edge of the window frame and it is, therefore, unnecessary to have the aforesaid accuracy of fit heretofore required in order to close the opening, this being accomplished by the contact of the flat surface of the flange 9 against the outer surface 10 of the window frame which thus provides for slight variation. The hook 13 may be arranged in connection with the eye 13' on the window frame to apply inward pull or pressure and the outer flange thus produces with

the window frame, a much tighter joint than can possibly be obtained by a frame portion which fits within the opening.

It will be seen, furthermore, that when a frame is made to fit within the opening, a slight warpage of the outer rails of the screen will cause an opening up between the window frame and the rails of the screen so as to permit flies and other insects to have access to the room, while with applicant's screen, inward pressure by a hook or hooks will always apply pressure between the abutting surfaces of the flange and window frame and this pressure may be applied to straighten out any possible warpage.

Furthermore, I have provided very desirable features in the movement of the entire screen outwardly to provide access for the washing of the window on the outside, and also in the dropping, instead of the conventional raising upwardly of the screen, I am enabled not only to retain the same in opened position without the use of sticks or other obstructing devices, but also to enable the screen to be used without interference with the conventional awning.

Having described my invention, I claim:—
An outside screen for windows comprising a single outside frame having top and bottom rails and stiles, said frame being provided along the top rail and along the stiles with a rectangular rabbet formed by an inwardly-projecting member and a flange extending at right angles thereto, said rabbeted portion being adapted to fit over and engage with the corner of the window formed at the outermost side of the window frame, the flange of said rabbeted portion lying flat all around against the outer surface of the window frame and in parallel relationship to the wall containing the window, means for mounting the said outside frame to permit movement toward and away from the said outer surface of the window frame, and means for fastening said screen to the window frame, whereby a tight joint between the top rail and the stiles and the said outer surface of the window frame is provided.

In witness whereof, I have signed my name to the foregoing specification.

CHARLES W. HARRING.
